UNITED STATES PATENT OFFICE.

EDGAR D. DICKINSON, OF BEVERLY, AND REGINALD G. STANDERWICK, OF MARBLE-HEAD, MASSACHUSETTS, ASSIGNORS TO GENERAL ELECTRIC COMPANY, A CORPORATION OF NEW YORK.

ELASTIC-FLUID TURBINE.

Application filed October 16, 1925. Serial No. 62,839.

The present invention relates to elastic fluid turbines and especially to turbines provided with what are known as oil governors. In connection with such turbines, it has been 5 the practice to provide an oil pump for the governor mechanism and a second oil pump for the lubricating system.

The primary object of our invention is to provide an improved arrangement whereby 10 the same oil pump may be utilized successfully for both the oil governor and the lubricating system, whereby in connection with a turbine installation one pump may be dispensed with.

15 A further object of our invention is to provide an improved form of adjusting and pressure relief valve structure possessing certain advantages as hereinafter pointed out.

20 For a consideration of what we believe to be novel and our invention, attention is directed to the accompanying description and the claims appended thereto.

In the drawing, Fig. 1 is a side elevation 25 of an elastic fluid turbine equipped with a mechanism embodying our invention, a part of the mechanism being shown in section, and Fig. 2 is a sectional view through our improved adjusting and pressure relief valve structure.

30 Referring to the drawing, 1 indicates an elastic fluid turbine which may be of any suitable type and may drive any desired load. In the present instance, it is shown 35 as having its shaft 2 coupled directly to the armature of a generator 3. 4 indicates the bearings for shaft 2, and 5 indicates the exhaust conduit of the turbine. The admission of elastic fluid to the turbine is regulated by a suitable valve structure 6. This 40 valve structure is indicated only in outline and may be of any suitable type. Its detail structure forms no part of the present invention. The valve mechanism 6 is opened 45 and closed by a piston 7 which is suitably connected to it. Piston 7 moves in a cylinder 8. When it moves upward it opens the valve means 6 and when it moves downward closes it. Piston 7 is connected by a 50 stem 9 to a head 10 which slides on an extension 11 of cylinder 8. The admission of operating fluid to cylinder 8 is controlled by a pilot valve structure 12 of usual and well

known arrangement. Piston 7 and cylinder 8 and the pilot valve structure 12 form a 55 well known type of fluid actuated motor such as is employed usually for operating the controlling valve means of an elastic fluid turbine.

The stem 13 of the pilot valve structure is 60 pivotally connected to a lever 14 which at one end is fulcrumed on a vertical spindle 15. The other end of the lever 14 is connected by a vertical spindle 16 to a piston 17 which moves in a cylinder 18. Surrounding 65 a portion of spindle 16 is a spring 19 which at its lower end is rigidly connected to a spring plug 20 which forms also a cover for cylinder 18. The other end of spring 19 is rigidly connected to a spring plug 21 ad- 70 justably mounted on spindle 16. Spring 19 serves to bias piston 17 to its lowermost position in cylinder 18, this being the position shown in the drawing, and serves to oppose upward movement of piston 17. 75

Fixed on pilot valve stem 13 is a collar 22 upon which rests the lower end of a spring 23. The upper end of spring 23 engages a collar 24 carried by an arm 25 fixed to head 10. Pilot valve stem 13 extends loosely 80 through an opening in collar 24 and arm 25.

With the arrangement so far described, when piston 17 moves upward in cylinder 18 it lifts the left hand end of lever 14, the lever pivoting on the upper end of spindle 85 15. This lifts pilot valve 12 so as to admit actuating fluid to the upper side of piston 7 and permits it to escape from the under-side. This causes piston 7 to move downward in cylinder 8 to close off somewhat the 90 valve means 6, thereby decreasing the amount of elastic fluid being supplied to the turbine. When piston 7 moves downward, it carries with it the head 10 and arm 25, and arm 25 in moving downward restores the 95 pilot valve to its original position, through the intermediary of spring 23, collar 24 and the pilot valve stem 13, the movement taking place in opposition to spring 23, and at the same time restoring piston 17 to its original 100 position.

When piston 17 moves downward in cylinder 18 opening movement of the valve means 6 is effected in the same general manner as that just described. This is a known 105 valve regulating means and in itself forms

no part of our present invention. The pressure which moves piston 17 in cylinder 18 is supplied to it by a pump 26 driven from the turbine shaft, the pump being of a type 5 wherein the pressure created by it varies in accordance with the speed at which it is driven.

Pump 26 is driven from the turbine shaft through a suitable worm gearing 27 and 10 serves to supply oil to both the oil governor mechanism and to the lubricating system for the turbine. The discharge side of pump 26 is connected by a pipe 28 to the lower end of cylinder 18, whereby it serves 15 to supply pressure to the under side of piston 17. Connected to pipe 28 is a discharge pipe or by-pass pipe 29 which leads to an adjusting and pressure relief valve structure 30. This structure comprises a cylindrical casing 20 31 closed at its two ends by heads 32 and 33. It is provided with partition walls 34 and 35 which serve to define a variable pressure chamber 36, a constant pressure chamber 37, and a discharge chamber 38. Pipe 29 is 25 connected to variable pressure chamber 36. In wall 34 is a passage 39 which serves to connect chamber 36 to chamber 37 and in wall 35 is a passage 40 which serves to connect chamber 37 to chamber 38. The flow of 30 oil through passage 39 is controlled by a valve 41 on the end of a valve stem 42 having an operating wheel 43. Valve stem 42 has a threaded connection with head 33 so that by turning the valve stem the position of valve 41 in passage 39 may be adjusted to open and close the valve. The 35 flow of oil through passage 40 is controlled by pressure relief valve 44 which is loosely mounted on stem 42. On the threaded portion of stem 42 is a nut 45 which is held from turning by a lock nut 46. Located between nut 45 and valve 44 is a spring 47 which serves to bias valve 44 toward closed position. This forms a spring pressed relief 40 valve, and nut 45 forms a means whereby the setting of the relief valve may be adjusted by changing the tension of spring 47. With the arrangement shown, it will be seen that when stem 42 is turned to move valve 45 axially nut 45 moves with the stem so that when stem 42 is turned in a direction to close valve 41, the tension of spring 47 is increased and when it is moved in a direction to open valve 41 the tension of the spring 50 is decreased. Also spring 47 can be set initially or be adjusted at any time by removing head 33 and turning nut 45 on stem 42.

Connected to constant pressure chamber 60 37 is a pipe 48 which conveys oil to the bearings of the turbine or other parts requiring lubrication. In the present instance, it is shown as conveying oil to a header 49 from which oil is distributed to

pipes 50 leading to the bearings, the flow of 65 oil from the header to the pipes being controlled by suitable valves 51. Connected to discharge chamber 38 is a pipe 52 which may be considered to form a continuation of discharge or by-pass pipe 29 and which conveys 70 oil back to the oil tank in which the pump is located, the same being indicated at 53.

When the turbine is running, pump 26 delivers oil at a pressure proportional to the 75 speed of the turbine. This oil pressure is conveyed from the discharge side of the pump through pipe 28 to the underside of piston 17. Oil from pipe 28 flows back to tank 53 by way of pipe 29, variable pressure 80 chamber 36, constant pressure chamber 37, discharge chamber 38 and pipe 52. A portion of the oil flowing into constant pressure chamber 37 is carried by pipe 48 to the lubricating system for the turbine. Valve 85 41 is set so that when the turbine is running at the desired speed, the flow of oil through it will be such as to maintain in pipe 28 a pressure which, acting on the lower surface 90 of piston 17, serves to balance spring 19 and maintain valve means 6 in a position to admit to the turbine elastic fluid sufficient to maintain the turbine speed. If the speed of the turbine increases, the pressure increases, thereby effecting an upward movement 95 of piston 17 and, in the manner already described, a closing of valve means 6 through the oil governor mechanism, to decrease the supply of elastic fluid to the turbine, bringing the speed back to normal. 100 On the other hand, if the speed of the turbine decreases, then the oil pressure decreases, permitting piston 17 to move downward to effect an opening movement of valve means 6 so as to supply more elastic fluid 105 to the turbine to bring its speed up to normal. Valve 44 is held by spring 47 and such spring is set to maintain the desired definite pressure in chamber 37.

In the operation of an oil governing mechanism, it is necessary that the oil pressure in the discharge pipe of the pump should remain constant as long as the turbine speed remains constant, and if this is to be accomplished, it is necessary that the pressure in 110 the region to which the discharge pipe or by-pass pipe discharges be maintained constant. As is obvious, if the pressure in the region to which the by-pass pipe discharges varies, the pressure in the pressure pipe will vary because of the resulting change in the rate of flow of oil from the pipe due to the change in the pressure. This requires, in the present instance, that the pressure in chamber 37 must be maintained constant. This is accomplished by means of the pressure relief valve 44, the pressure maintained being one suitable for supplying oil to the

lubricating system of the turbine. Valve 44 is held by spring 47 and such spring is set for the desired pressure in chamber 37.

When the turbine is operating, oil flows 5 continuously from chamber 36 past valve 41 to chamber 37. From chamber 37 part of the oil flows through pipe 48 to the lubricating system and the remainder flows past pressure relief valve 44 to return pipe 52. 10 Valve 44 is held open for the escape of oil past it by the pressure of the oil in chamber 37. If the pressure in chamber 37 tends to increase due to decrease in the requirements for lubricating oil, for example, then 15 valve 44 will be opened further against the action of spring 47 to permit more oil to flow through passage 40. On the other hand if the pressure in chamber 37 tends to decrease due to an increase in the demands of the 20 lubricating system for example, then valve 44 will move toward closed position under the action of spring 47 thereby permitting a lesser amount of oil to escape through passage 40 and bringing the pressure in chamber 25 37 back to the desired normal constant value again.

When the setting of valve 41 is changed to vary the speed of the turbine, the quantity of oil supplied to chamber 37 decreases or 30 increases depending upon whether valve 41 is opened further to increase the speed of the turbine or is closed further to decrease the speed of the turbine. If a larger quantity of oil is supplied to chamber 37, then with the same setting of spring 47 as 35 before the pressure in chamber 37 would increase somewhat because an increased pressure would be required in order to open valve 44, the additional amount necessary 40 to pass the extra oil. On the other hand, if a smaller quantity of oil is supplied to chamber 37 then with the same setting of spring 47, the pressure in chamber 37 would decrease somewhat due to the smaller amount 45 of oil to be passed through passage 40. When changing the setting of valve 41 therefore, to change the speed of the turbine, it is desirable to change also the setting of spring 47 in order to maintain constant the 50 pressure in chamber 37. This, it will be seen, is accomplished by our improved construction, for, due to the arrangement of the nut 45 which travels with stem 42, the tension of spring 47 is automatically increased 55 whenever valve 41 is moved toward closed position and decreased when it is moved toward open position.

By this arrangement, there is maintained 60 always in chamber 37 the same pressure irrespective of the setting of valve 41. By the arrangement, therefore, we are enabled to maintain a constant pressure on the discharge side of valve 41 and at the same time a pressure suitable for supplying oil to the parts of the turbine to be lubricated.

Our improved pressure relief valve structure, while it is well adapted for use in the arrangement shown, is not necessarily limited to this particular use but may be used in connection with other apparatus to 70 which it may be found adapted.

In accordance with the provisions of the patent statutes we have described the principle of operation of our invention, together with the apparatus which we now consider 75 to represent the best embodiment thereof, but we desire to have it understood that the apparatus shown is only illustrative and that the invention may be carried out by other means. 80

What we claim as new and desire to secure by Letters Patent of the United States, is:—

1. A valve means for use with an elastic fluid turbine having an oil governor mechanism including a moving part, a pump, a conduit for conveying oil from the pump to the moving part, and a by-pass conduit connected with the first-named conduit, said valve means comprising walls defining a 90 chamber into which the by-pass conduit discharges, a valve controlling the flow of oil from the by-pass conduit to said chamber, a pressure relief valve controlling flow of oil from said chamber and serving to maintain 95 constant pressure in said chamber, conduit means for conveying oil from said chamber to parts of the turbine requiring lubrication, and means for simultaneously adjusting the first-named valve and the setting of the pressure relief valve.

2. A valve means for use with an elastic fluid turbine having an oil governor mechanism including a moving part, a pump, a conduit for conveying oil from the pump to the moving part, and a by-pass conduit connected with the first-named conduit, said valve means comprising walls defining a chamber into which the by-pass conduit discharges, a valve controlling the flow of oil 105 from the by-pass conduit to said chamber, a pressure relief valve controlling flow of oil from said chamber and being movable in response to pressure in said chamber, between the closed and open positions, independently 110 of the first-named valve to maintain constant pressure in said chamber, a conduit means for conveying oil from said chamber to parts of the turbine requiring lubrication, means for adjusting the first-named valve, 115 and means operated by such adjusting means for varying the setting of the pressure relief valve.

3. A valve means for use with an elastic fluid turbine having an oil governor mechanism including a moving part, a pump, a conduit for conveying oil from the pump to the moving part, and a by-pass conduit connected with the first-named conduit, said valve means comprising walls defining a 130

- chamber into which the by-pass conduit discharges, a valve controlling the flow of oil from the by-pass conduit to said chamber, a spring-pressed pressure relief valve controlling the flow of oil from said chamber, a conduit for conveying oil from said chamber, and means for simultaneously adjusting said first-named valve and the setting of the spring of the pressure relief valve.
- 10 4. In combination, walls forming a chamber, said walls being provided with an admission opening, and a discharge opening, a valve in the admission opening, a pressure relief valve in the discharge opening, said valve being movable to the open position in response to pressure independently of the first-named valve, and a common means connected with both valves for simultaneously adjusting the degree of opening of the first-named valve and the setting of the pressure relief valve.
- 15 5. In combination, walls forming a chamber, said walls being provided with an admission opening and a discharge opening, a valve in the admission opening, a spring-pressed relief valve in the discharge opening, said valve being movable to the open position in response to pressure independently of the first-named valve, and a common means connected with both valves for simultaneously adjusting the first-named valve and the setting of the pressure relief valve.
- 20 6. In combination, walls forming a chamber, said walls being provided with an admission opening, and a discharge opening, a valve in the admission opening, a pressure relief valve in the discharge opening, the last-named valve being movable to the open position in response to pressure independently of the first-named valve, an operative stem for the first-named valve by which its degree of opening is adjusted, and means moved by said stem for adjusting the setting of the spring of the relief valve.
- 25 7. In combination, a casing having a fluid inlet at one end and a fluid outlet at the other end, spaced partition walls in said casing between the inlet and outlet ends providing a pressure chamber therein, a valve providing a variable fluid connection between the inlet end of the casing and the chamber, a relief valve providing a fluid connection between the chamber and the outlet end of the casing, a spring by which said relief valve is closed against the pressure in the chamber, a valve stem by which the first-named valve is operated, and means carried by said stem and connected with the relief valve spring for varying the spring pressure acting upon said valve when the first-named valve is operated.
- 30 In witness whereof, we have hereunto set our hands this 14th day of October, 1925.

EDGAR D. DICKINSON.
REGINALD G. STANDERWICK.
